UNITED STATES PATENT OFFICE.

WILSON P. DODSON, OF PHILADELPHIA, ASSIGNOR OF ONE-HALF TO ALEXANDER H. EGE, OF CUMBERLAND COUNTY, PENNSYLVANIA.

RAILROAD-SWITCH.

SPECIFICATION forming part of Letters Patent No. 259,001, dated June 6, 1882.

Application filed October 7, 1881. (No model.)

To all whom it may concern:

Be it known that I, WILSON P. DODSON, of Philadelphia, in the county of Philadelphia and State of Pennsylvania, have invented certain new and useful Improvements in Railroad-Switches; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to improvements in railroad switches and frogs, by which trains of cars in passing in either direction, whether upon the main track or siding, will be prevented from derailment under any and all circumstances arising from a misplaced switch.

In referring to the drawings, Figure 1 is a plan view, showing the main track and switch, with the latter open to the former in full lines and closed in dotted lines. Fig. 2 is a longitudinal section in line $x-x$ of Fig. 1. Fig. 3 is a plan showing the main track and siding with a frog to be used in connection with the depressed track, of which the latter forms a part. Fig. 4 shows a longitudinal section on line $y-y$ of Fig. 3, with the part of deepest depression of the main track removed. Fig. 5 is a transverse section through the road-bed and rails, showing more particularly the arrangement of the springs controlling the pointed rail.

For the sake of brevity of description, I shall call the direction of a train moving on the main track in direction of the arrows $a-a$ as "up," while the opposite direction will necessarily be called "down," and need not otherwise be specially designated.

In speaking of the details of my invention, I propose to construct the permanent-track rail A of a depressed shape or contour vertically, said depression extending gradually upon an incline downward from some point, as b , up the main track toward the opening of the switch until it reaches a maximum depth somewhat in excess of the height of the flanges of the wheels of a railway car or engine at or near the point e , at or about opposite the pointed extremity of the movable switch-rail

B', from which point e said maximum depth of depression is maintained in the same direction until the flanges of the wheels of a train passing from the main track to the siding shall have had ample scope to clear the horizontal surface of said depression of the main-track rail A, from which point the depression takes an upward incline until a height is attained equal to that of the general level of the road-bed or track below the point b , or before the commencement of the depression, said height being indicated in the drawings by the point c , after which the aforesaid general level is maintained both in the case of the main track and siding until the point d , Fig. 3, of the prolonged main-track rail A is reached in close proximity to the entrance of the frog O, when the same contour or mode of depression of said main-track rail A is repeated, and terminating at the point i in the tongue of the frog, where the prolongation of the switch-rail B' intersects the main-track rail A and conserves the same function without variation as in the limits of the switch proper.

The permanent switch-rail B of the siding is made to lie closely against, and, if necessary, rigidly connected with, the depressed rail A laterally, and then spiked down firmly to the underlying cross-ties. It may also be rigidly bolted fast to said depressed main-track rail A, but in either case made to perform with the latter the same combined function, whether located in the switch or frog. The location of the extremity of the switch-rail B is at a short remove from the commencement of the depression of said main-track rail A, as at f , and thence continues said switch-rail B in a horizontal line parallel with said main-track rail A until the said rail B reaches the point f' , from which point said track-rail B of the siding is elbowed or bent at such a curve as will allow of the easy passage of the flanges of the wheels of an ingoing train between said point f' and the main-track rail A, when said switch-rail B is prolonged parallel to the continuation of the opposite track-rail of the siding, or prolongation of the pointed switch-rail B', as hereinafter more fully set forth.

With regard to the construction of the switch-rail B', I propose to make the same pointed at 100

its free end at an angle more or less acute, as may be required by the circumstances of the case, while said switch-rail is so connected with the other co-ordinate parts of the switch as 5 shall render the same capable of being moved laterally at its pointed or free end in consequence of being pivoted at the opposite end as securely as may be desired. As regards the further construction of said pointed switch- 10 rail B', I propose to make the same wedge-shaped more or less throughout the greater part of its length, having the pivotal extremity of said pointed rail B' of such lateral thickness as will enable it to perform, when re- 15 quired, the function of a guard-rail, which it will be required to do in the case of a train passing up the main track with the switch closed for the siding. To secure this required thickness I propose either to make said pointed 20 rail of a single heavy rail, planed down to the required lateral dimensions, or to use a T-rail of the ordinary dimensions, planed at the one extremity to a desired angle, and subsequently re-enforced by bolting a supplemental pointed 25 rail into the outer shank of the same when in position, which combination will in most cases be sufficient, owing to the fact that the pressure of the flanges of the wheels will always be inward when said pointed switch-rail performs 30 the function of a guard-rail or in the direction of the greatest resistance. As a re-enforcement of said inner resisting power I propose to locate one or more shoulders or stops, v v, at the limit of the inner range of said pointed rail B', 35 said shoulders being so constructed as to engage snugly into the shank or against the tread of said switch-rail, as may be most desirable. When it is required to perform the desired lateral movement of said pointed switch-rail 40 B' in order to shunt a passing car or train, I propose to accomplish the same by means of a switch-lever or equivalent appliance, F, and switch-bar E, so adjusted and coupled together as to effect the desired lateral range, but at 45 the same time to limit the movement strictly to said range, as hereinafter more fully set forth.

The stop or shoulder K is permanently and firmly attached or bolted fast to the sleeper or 50 cross-tie L, on which the switch-bar moves, and against which the remote extremity of said bar impinges, and thus performs the function of defining the limits of the inward thrust of the same.

55 The switch-bar E is also furnished with a suitable housing, H, bolted fast thereto, the arms or bearings a⁴ a⁵ of which are perforated or otherwise suitably equipped for the reception of the spring-bar G. Said spring-bar G 60 is bolted or otherwise securely attached at the one extremity to the pointed switch-rail B', while the opposite extremity passes through the perforations or receiving-seats of the arms of the housing H and the bore or caliber of the 65 spiral or other suitable springs confined within or between said arms, said springs being con-

fined and limited in their longitudinal thrust or motion therein by means of the adjusting-nuts n n' and the arms of the housing, said bar G being also pivoted at or near its bolted end 70 when it is desirable to secure a ready mode of adjustment to the short radial requirements of the pivoted switch-rail B'—a demand that obtains when the line of direction of the main track-rails is curved more or less sharply 75 within the limits of the switch proper; or if in practice it is found more convenient I may adopt a vice versa construction, supplying the spring-bar G with the housing H, and the switch-bar E with the spiral spring or springs, 80 re-enforced with the other necessary aforementioned details.

The spiral springs s s' move freely upon the periphery of the screw-threaded spring-bar G, have a range of longitudinal movement more 85 or less extensive under compression, and are separated from each other, end from end, by the adjustable nuts n n', usually located about midway between the bearing-points of the arms of the housing H, said nuts operating to perform the function of increasing or relaxing the tension of the spirals, according to the requirements of the case. These springs s s' may be re-enforced in strength, if need be, by the introduction of a similar spiral spring of smaller 95 caliber within the bore of the outer or larger spiral spring in such a manner as may be most convenient in practice. The guard-rail C is permanently bolted fast to the cross-ties or sleepers between the main-track rails, and located parallel with and about two inches from the permanent main-track rail A', and made to maintain said parallelism more or less until the pointed extremity of the switch-rail B' is reached, from which point said 100 guard-rail C may be inclined inward or flared more or less, so as to attain a position about parallel to said pointed switch-rail B' when said switch-rail is open for the siding.

The permanent guard-rail C' is also placed 110 parallel to the main-track rail A, being located about two inches from the same in order to admit of the free passage of the flanges of the wheels of the passing car or train, and thus to perform the usual function of such appliances 115 in preventing a too great lateral movement of the wheels toward the opposite side of the road-bed, and thus operating to protect the pointed end of the switch-rail B' from too great friction and consequent wear in the case of the 120 contact therewith of the flanges of the wheels of the cars on that side when a train is being shunted onto the siding. Said guard-rail C' needs only be made of such length as will enable it to perform said function the most effect- 125 ively.

By an inspection of the action of the flanges of the wheels of an ingoing train passing from the main track onto the siding, as shown in dotted lines in Fig. 1, it will be perceived that 130 when the tread of the wheels upon the left arrive at the commencement of the depression

they move without jar upon the horizontal surface of the permanent switch-rail B of the siding in a right line until said wheels reach the point *e* of greatest depression, when said 5 wheels are deflected obliquely and the flanges of the same move freely over the concave surface of the depression without obstruction, in consequence of the impact of the flanges of the 10 wheels of the train or car on the right against the inner edge of the tread of the switch-rail B', said deflection being made easily possible by such bend or elbow deflection of said switch-rail B as will secure its general parallelism with the switch-rail B', and thus attain with 15 the latter the co-ordinate bearings of the desired siding in its functional integrity complete. Now, directing the attention to the action of the flanges of the wheels upon the right or prolonged switch-rail B', when they arrive at the 20 intersection of the latter with the above-mentioned prolongation of the main-track rail A at the point of greatest depression, *i*, we will perceive that the same easy and uninterrupted passage of the flanges of the wheels of 25 the ingoing train over the main-track rail A obtains as transpired at the point *e* at the entrance of the siding.

The only change of construction found necessary in the mutually-supporting parts of the 30 frog O is that, instead of the horizontal support B'' of the depressed rail A above mentioned in its prolongation being deflected at the point *i*, as at *f'*, to constitute a part of the switch-rail B of the siding, it is simply deflect- 35 ed at a short angle or flared, and then termin- 40 ates in the wing N of the frog O. A similar termina- 45 tion or flaring transpires in the case of the prolonged switch-rail B', said rail being deflected at a short curve upon the inside of the main track A, and then terminating, thus 50 constituting the inner wing, M, of the frog O, as shown in Fig. 2. This slight change of construction above adverted to is rendered necessary simply from the fact of the engage- 55 ment of the flanges of the wheels with the above-mentioned parts of the frog O, being that of those wheels upon the side of the car opposite to that of those that engage with the corresponding parts in the switch proper. The 60 throat of the frog O is thus seen to be the point of greatest depression, *i*, while the tongue consists of the highest point, *r*, of the incline, and the pointed extremity of the permanent siding-rail D, said inclined prolongation of the main- 65 track rail A and said pointed permanent rail D being bolted securely together, or otherwise immovably attached at said point *r*, so as to afford the necessary prolonged bearings, re- 70 spectively, of both main-track and siding rails to secure the desired safe passage of a train over the frog in any desired direction. It is thus readily observable that the continuity both of the main-track rails A A' and the switch-rail B is fully maintained by an association of 75 80 85 90 95 100 105 110 115 120 125 130 135 140 time most successfully conserve the end proposed, either of admitting of the passage of a train upon the main track at any speed desired or of shunting the same onto the siding with equal safety and facility, a degree of solidity and strength being thus attained most desirable and absolutely necessary in view of the vital interests at stake in the premises.

It now remains to show how a car or train may be absolutely secure from derailment in passing down the main track, the switch being left open to the siding, or from the siding onto the main track, the switch being closed to the side track, either from accident or design in either case, and how this end is attained without derangement or accident to the mechanism of the switch, and consequent danger of destruction of both life and property in the case of trains in transit. Let us take, for instance, the former case, the switch being open for the siding, and the train coming down the main track, in which case the pointed switch-rail B' is held by the switch-lever against the side of the permanent track-rail A', and the flanges of the wheels of the downgoing train, entering wedge-like into the angle between said rails, force the same apart at their point of contact against the pressure of the spring sufficiently to admit of the passage of the wheels so engaging, thus imparting to the pointed switch-rail B' a lateral movement. The wheels having passed the point, the spring S will restore the pointed switch-rail B' to its normal position of engagement with the main track-rail A' occupied by said switch-rail B' before said supposed passage of a train; or, again, on the other hand, take the case in which the switch is closed for the side track, and the train attempts to pass from the siding onto the main track, the pointed switch-rail B' being locked to a position of close contact laterally against the fixed guard-rail C'. In the supposed case an opposite lateral movement takes place from what obtains in the former case, both by a similar wedging of the flanges of the wheels into the angle between the pointed switch-rail B' and the guard-rail C' in connection with the lateral pressure of the flanges against said switch-rail B', from the fact that when the latter is in the supposed position there is a convergence of the opposite rails of the siding in the direction of the opening of the switch—a result attainable from the compressibility of the spiral spring s', which in this case performs the same function as the spiral spring s in the former case, and which similarly, as in said former case, upon the removal of the pressure, has sufficient elasticity to force said switch-rail B' back to its normal position (to which I have supposed it previously set locked) after the passage of the train.

It now remains to show the functions of the guard-rails D' and D'', located opposite to the frog O, and lying between the rails, respectively, of the main line and the siding. In the

case of the train passing in either direction upon the main track, the guard-rail D', being permanently located within the prolongation of the main-track rail A' and about two inches 5 from the same at the central point of said guard-rail, performs the office of preventing a too great lateral motion of the wheels of the same to said limits, and thus secures the passage 10 of the wheels upon the opposite track unerringly between the rail A and guard-rail M, and thus conserving the passage of the train over the frog O, even though the train should lurch from any cause to either side of the road-bed. 15

In the case of a train passing in either direction upon the siding, the guard-rail D'' is located within the prolongation of the switch-rail B opposite the frog O, and in all other respects 20 similarly situated, as in the case of the guard-rail D', and for the performance of a similar function in securing the safe passage of the wheels of the train over the co-ordinate bearings of the frog and track, as in the analogous 25 case of a train passing over the main track.

In practice it may be found most convenient in the case of both the guard-rails D' and D'' to flare them inward from some central point, 30 as h, toward each extremity of the same, to such an extent from the track-rails, respectively, as to admit of the easy passage of the flanges of the wheels of an ingoing or passing train, in consequence of the engagement or impingement 35 of the same against said guard-rails with a gradually-increasing pressure to said point h, where the maximum pressure of said flanges should obtain.

In a previous application, serial No. 26,765, 40 I have shown in a railroad-track a depressed main track in connection with the usual siding without claiming the same, broadly.

I am aware of the United States Patents Nos. 48,470 and 69,599, and English No. 3,183 45 of 1873, to Wm. Wharton, Jr., and to such construction as is shown in them I make no claim.

What I claim as new, and desire to secure by Letters Patent, is—

1. In a railroad switch and frog, the depressed rail A of the main track and the rail 50 A' of the same, in combination with the permanent elbow-rail B and the pointed and movable switch-rail B' of the siding, as and for the purpose hereinbefore set forth.

2. In a railroad-switch, the combination, with 55 the main-track rails A and A', the former being depressed, and the permanent elbow-rail B, and the pointed and movable switch-rail B' of the siding, of a suitable spring or springs for actuating the pointed switch-rail B' laterally 60 for the purpose of shunting a car or train from said main track onto the siding, or vice versa, substantially as described.

3. In combination with the springs s s', the housing H, and spring-bar G, the adjusting-nuts n n', movable on the said screw-threaded spring-bar G, to increase or diminish the tension of said springs, substantially as and for the purpose hereinbefore set forth. 65

4. The combination, with the main track A 70 A' and the siding B B', of the depressed frog O and supporting-rail B'', substantially as and for the purpose set forth.

5. A railroad-frog provided with a depressed main-track rail, and having the necessary siding and guard rails associated therewith, substantially as and for the purpose set forth. 75

6. The combination, with the throw-bar and switch-point, of screw-threaded spring-bar G, the springs s s', and adjustable nuts n n', where-by the tension of said springs may be regulated independently of each other, as and for the purpose set forth. 80

In testimony that I claim the foregoing as my own I affix my signature in presence of two 85 witnesses.

WILSON P. DODSON.
